RAZOR BLADE SHARPENER

John R. Dickey, Media, Pa.

Application May 29, 1935, Serial No. 24,062

2 Claims. (CL. 51—161)

The present invention relates to razor blade sharpening devices, and particularly to devices of the type in which a blade is carried in pressure contact with the inner surface of a tubular sharpening element.

It is well-known that a safety razor blade may be sharpened by moving it back and forth with the finger on the inner cylindrical surface of a glass tumbler, and it has been proposed to employ apparatus comprising a tubular element of glass, or like material, in combination with a rotatable carrier for maintaining a blade against the inner wall of the tubular member, and moving it back and forth to sharpen the edge thereof. So far as I am aware, the devices of this nature which have heretofore been proposed are complicated in structure by reason of the large number of parts and relatively expensive to manufacture, and such devices are inefficient in operation by reason of the fact that no means are provided for effecting a fine adjustment of the pressure with which the blade is maintained against the sharpening element. In order to obtain a keen edge, it is necessary to adjust such pressure contact carefully and within relatively narrow limits.

Accordingly, the object of the present invention is to provide a sharpener of this type which is characterized by simplicity of construction, and which may be operated with ease and facility, and at the same time to provide means for effecting a delicate adjustment of the pressure with which the blade is held in contact with the sharpener element. The device of my invention is further characterized by a small number of parts of relatively inexpensive material.

Other objects and advantages characterizing my invention will become more fully apparent from the description hereinafter set forth of one example or embodiment thereof, having reference to the accompanying drawing. Of the drawing:

Fig. I represents a view, partly in cross section and partly in side elevation, of a razor blade sharpener of my invention; and

Fig. II represents a cross section of the same, taken as indicated by the lines II—II of Fig. I. With reference to the drawing, there is shown a tubular sharpening element 1 which may be made of glass or like material, and which presents a smooth inner wall around which a razor blade 2 is carried by means of a blade holder 3. The blade holder 3 is mounted on a shaft 4 which extends centrally through the tubular sharpening element 1, and which is journaled

for rotation in bearing members 5 secured to the ends of the tubular body 1. Rotation of the shaft 4 is accomplished by turning a crank 6 secured to one end of the shaft.

Each bearing member 5 preferably takes the form of a clip comprising a relatively narrow strip of metal extending diametrically across the end of the tubular body 1 and having flanges 7 for gripping the outer wall of the tubular body with sufficient pressure to prevent relative rotation between the parts. The rotatable shaft 4 has an intermediate portion 8 of rectangular cross section in the center of which, as shown in Fig. II, there is provided a square slot 9. The blade holder 3 has a square shank 10 fitting within the slot 9 and guided thereby with capacity for sliding movement in a direction radially of the axis of the shaft 4. The blade holder 3 carries at the end thereof an arcuate foot 11, the bottom of which may be roughened to provide frictional contact with the blade 2. I have found, however, that when the position of the blade holder 3 is properly adjusted, the pressure imposed upon the blade and tending to flex the same slightly, is sufficient to prevent the blade 2 from slipping, so that it is at all times maintained in the proper position between the foot 11 and the inner wall of the tubular body 1 while the handle 6 is being turned.

The blade holder 3 has a central threaded bore 12, and a correspondingly threaded thumb screw 13 fits within the bore 12 and serves as a means for adjusting the position of the blade holder with relation to the sharpening element 1. Desirably the thumb screw 13 has a knurled head 14. Movement of the thumb screw 13 in the direction of its longitudinal axis is prevented by means of a U-shaped clip 15 which extends over the top of the knurled head 14, and is united at its ends to the central portion 8 of the shaft 4. Accordingly, a turning movement of the thumb screw 13 causes sliding movement of the shank 10 of the blade holder 3 within the slot 9, and in this manner a fine adjustment is afforded so that the razor blade 2 is held against the sharpening element 1 with the desired pressure.

It will be noted that the end bearing members 5 are so constructed as to permit ready access into the tubular body 1 with the fingers, whereby the knurled head 14 of the thumb screw 13 may be turned and the above described adjustment may be readily accomplished. Moreover, the insertion of the blade 2 beneath the foot 11 of the blade holder 3 is a simple matter and may easily be accomplished by turning the handle 6

to a position in which the end of the blade holder 3 is readily accessible.

It will be apparent that the device of this invention is made up of parts which are simple to construct and assemble and inexpensive to manufacture. At the same time, the device is reliable and efficient in its operation, and avoids the difficulties which have heretofore been encountered because it provides a delicate, though 10 easy, adjustment of the pressure of the blade against the sharpening element.

While I have described one example of my invention, it will be apparent that various changes may be made in the form of the apparatus herein described and illustrated, without departing from the spirit of my invention as defined in the 15 annexed claims.

Having thus described my invention, I claim:

1. A razor blade sharpener comprising a tubular sharpening element, bearing members at the ends thereof, a slotted shaft supported for rotation by said bearing members, a blade holder guided within said slotted shaft and extending radially therefrom to carry a blade against the 20

inner surface of said sharpening element, and a thumb screw accessible through the ends of said sharpening element having a threaded engagement with said blade holder and serving as a means for adjusting the position of said blade 5 holder with relation to the sharpening element, and means on said shaft for preventing axial movement of said thumb screw.

2. A razor blade sharpener comprising a tubular sharpening element, bearing members at the ends thereof, a shaft supported for rotation by said bearing members and having a central portion of rectangular cross section, with a slot therein, a blade holder fitting in said slot and extending radially from said shaft to carry a 15 blade against the inner surface of said sharpening element, a thumb screw accessible through the ends of said sharpening element having a threaded engagement with said blade holder and serving as a means for adjusting the position of 20 said blade holder with relation to the sharpening element, and means on said shaft for preventing axial movement of said thumb screw.

JOHN R. DICKEY.
